UNITED STATES PATENT OFFICE

161,015

CONDIMENT CONTAINER HOLDER

Erving R. Gillette, Twentynine Palms, Calif.

Application April 25, 1950, Serial No. 9,467

Term of patent 14 years

(Cl. D44—29)

To all whom it may concern:

Be it known that I, Erving R. Gillette, a citizen of the United States residing at Twentynine Palms, in the county of Riverside and State of California, have invented a new, original, and ornamental Design for a Condiment Container Holder, of which the following is a specification, reference being had to the accompanying drawing, forming part thereof.

Fig. 1 is a front perspective view of a condiment container holder showing my new design.

Fig. 2 is a rear perspective view thereof.

I claim:

The ornamental design for a condiment container holder, as shown.

ERVING R. GILLETTE.
